UNITED STATES PATENT OFFICE.

SHERMAN FEE AND OTTO T. TRAISER, OF OSCEOLA, WISCONSIN.

BAG-HOLDER.

1,030,882.

Specification of Letters Patent. Patented July 2, 1912.

Application filed March 2, 1912. Serial No. 681,255.

To all whom it may concern:

Be it known that we, SHERMAN FEE and OTTO T. TRAISER, citizens of the United States, residing in Osceola, Polk county, in the State of Wisconsin, have invented new and useful Improvements in Bag-Holders, of which the following is a specification.

Our invention relates to improvements in bag holders. Its object is to provide an adjustable device of this class, simple and durable in construction and adapted to hold efficiently various sizes of bags in position to be filled.

A further object is to provide yielding and conveniently operated means for engaging, opening and holding a bag in such position.

In the drawings Figure 1 is a front elevation of our improved bag holder, showing the retaining arms (in dotted lines) in position to receive a bag, and also showing said arms extended to hold a bag for filling; Fig. 2 is a side elevation; Fig. 3 is an enlarged sectional view taken on the line 3—3 of Fig. 2; Fig. 4 is an enlarged sectional view taken on the line 4—4 of Fig. 2 and Fig. 5 is an enlarged detail view showing in plan the end of a bag retaining arm.

Referring to said drawings, we have provided a standard 10, which is hollow and square in cross section. This standard is supported by a base 11, to be attached to a floor in any convenient manner. The support 12 is arranged on the standard 10 and is provided with a thumb-catch 13 having an end 14 adapted to engage in the perforations 15 in said standard for adjusting said support thereon. The arms 16 are fulcrumed at their lower ends on the support 12 and are formed with loops 17 and hooks 18 at their upper ends for securing the mouth of a bag on said arms. The sleeve 19 is slideable on the standard 10 and is connected with the arms 16 by the links 20, said links being pivotally attached at their inner ends to said sleeve and at their outer ends to collars 21 adjustable on said arms. The rod 22 is slideable within the standard 10 and is perforated as indicated by the numeral 23. The sleeve 19 is provided with a thumb-catch 24, an end 25 of which extends through the slot 26 in the standard 10 and is adapted to engage in the perforations 23 in said rod, thus forming an adjustable connection between said sleeve and rod. The spring 27 is arranged on the standard between the sup-

port 12 and sleeve 19 to normally separate said parts and fold said arms. The foot lever 28 is pivotally and adjustably attached at one end to the base 11 and has a slotted pivotal connection at 29 with said rod 22. Pressure on this lever operates through the rod 22 to lower the sleeve 19 against the action of the spring 27, thus extending the arms 16. The lug 30 is arranged on the base 11 to engage said lever, when pressed beneath it, and secure said arms in extended positions.

In operation, the support 12 and sleeve 19 are adjusted respectively on the standard 10 and rod 22, so that upon movement of the lever 28 to its lowered position, the arms 16 will open and secure a bag of a particular size in position with its base resting on the floor. When the desired adjustment has been made the mouth of the bag is applied to the folded arms and the lever 28 is pressed with the foot to open the bag and secure the same in position to be filled. The arms 16 and hooks 18 yield to any undue strain on the bag, thus preventing damage thereto. The tension of these arms against the mouth of the bag may be varied for any adjustment of said arms by moving the collars 21 upon said arms. When the bag has been filled the lever 28 is released and the lugs 18 detached from the mouth of the bag.

What we claim as our invention and desire to protect by Letters Patent, is:

1. In a bag holder, a standard provided with a base, a support and sleeve slidably mounted upon the standard, a pair of spring arms fulcrumed at their lower ends on said support, each of said arms being provided at its upper end with a loop terminating in a resilient horizontal arm for holding a bag, collars adjustable on said arms, links pivotally connecting said collars with said sleeve, and means for moving the sleeve upon the standard and for holding said support and sleeve in position thereon.

2. In a bag holder, a hollow standard provided with a base, a support and sleeve both slidably mounted upon the standard, a pair of arms fulcrumed at their lower ends on said support and formed at their upper ends with arms for holding a bag, links connecting the arms with the sleeve, a rod movable within said standard, means for adjustably securing the support on the standard, means for adjustably securing the sleeve on said rod, a spring between said support and

- sleeve for normally separating same to fold said arms, and a lever on said rod for moving said sleeve against the action of said spring to thereby extend said arms.
- 5 3. In a bag holder, a hollow standard provided with a base, a support and sleeve slidably mounted upon the standard, arms fulcrumed upon the support, means on said arms for holding a bag thereon, links connecting the arms with the sleeve, a spring interposed between said sleeve and support, a foot lever on said base, a lug for locking said lever in position and a rod, slidable within said standard, connecting said sleeve and lever.
- 10 4. In a bag holder, a standard provided with a base, a support and sleeve both slidably mounted upon the standard, arms fulcrumed on the support and provided with means for holding a bag thereon, collars 20 slidable on said arms, links each pivotally connected at one end to the sleeve and at the other end to one of said collars and means for moving the sleeve upon the standard and for holding the support and sleeve in position thereon.
- 15 5. In a bag holder, a hollow standard provided with a base, a support and sleeve slidably mounted upon the standard, arms fulcrumed upon the support, said arms being 25 formed with loops and hooks at their free ends, links connecting the arms with the sleeve, a spring interposed between said sleeve and support, a foot lever on said base and a rod, slidable within said standard, connecting said sleeve and lever.
- 30 6. In a bag holder, a hollow standard provided with a base, a support and sleeve slidably mounted upon the standard, arms fulcrumed upon the support, said arms being 35 formed with loops and hooks at their free ends, links connecting the arms with the sleeve, a spring interposed between said sleeve and support, a foot lever on said base and a rod, slidable within said standard, connecting said sleeve and lever.
- 40 7. In a bag holder, a hollow standard provided with a base; said standard having a continuous slot and a vertical series of aligned perforations therein, a support and sleeve both slidably mounted upon the standard, arms fulcrumed on the support, means on said arms for holding a bag, links connecting the arms with the sleeve, a rod movable within said standard and provided with 45 a series of perforations, a thumb catch on the support for adjustably securing the same on the standard, a thumb catch on said sleeve adapted to protrude through said slot and engage in the perforations of said rod for 50 adjustably securing said sleeve thereto.
- 55 In witness whereof, we have signed our names to this specification in the presence of two subscribing witnesses.

SHERMAN FEE.
OTTO T. TRAISER.
